UNITED STATES PATENT OFFICE.

GEORGE B. MALTBY, OF CLEVELAND, OHIO, ASSIGNOR TO CLEVELAND CAR SPECIALTY COMPANY, OF CLEVELAND, OHIO, A CORPORATION OF WEST VIRGINIA.

ROOF-CARLINE.

No. 869,974.

Specification of Letters Patent.

Patented Nov. 5, 1907.

Application filed October 19, 1906. Serial No. 339,614.

To all whom it may concern:

Be it known that I, GEORGE B. MALTBY, of Cleveland, in the county of Cuyahoga and State of Ohio, have invented a certain new and useful Improvement 5 in Roof-Carlines, of which improvement the following is a specification.

The object of my invention is to provide a metallic roof carline, specially adaptable for use in the framing of railroad freight cars, which shall embody the features of strength, lightness, and economy of construction, and present simple and effective means for connecting and firmly supporting the ridge pole and purlins in their respective positions in the roof structure, and for being supported on the car side plates and acting as a tie between the opposite sides of the car.

To this end, my invention, generally stated, consists in the combination of two compression members of angle section, bent downwardly from their middle portions towards their ends, and a tension member or tie interposed between the compression members and connected thereto adjacent to its ends.

The improvement claimed is hereinafter fully set forth.

In the accompanying drawings: Figure 1 is a side view, in elevation, showing slightly more than one half in length of a roof carline embodying my invention; Fig. 2, a plan or top view of the same; Fig. 3, a view, similar to Fig. 1, showing a modification of structural detail; Fig. 4, a plan or top view of the roof carline of Fig. 3; Fig. 5, a vertical central section through that of Figs. 1 and 2; Fig. 6, a similar section through that of Figs. 3 and 4; and, Figs. 7 and 8, similar sections illustrating modified forms of the tension member or tie.

35 In the practice of my invention, I provide two compression members, 1, of rolled or pressed metal, which are of angle section, as, for example, ordinary commercial shape "angle bars", and are placed at a short distance apart, their horizontal portions being uppermost 40 and turned outwardly from their vertical portions, and being in line one with the other throughout their length. The compression members, 1, are flat at their middle portions, for a distance about equal to the width of the ridge pole, 4, of the car roof for which they 45 are designed, and are thence downwardly bent or inclined towards their ends, at and adjoining which they rest on the side plates, 2, of the car frame, at such angle as may be adapted to impart the desired pitch to the roof. As shown in Fig. 1, the compression members are continuously inclined from each side of the central flat ridge pole bearing to the inner sides of

the side plates, while in Fig. 3, they are flat for a short distance adjacent to each side plate and inclined for the remainder of the distance between the same and the ridge pole bearing.

55

A tension member or tie, 1^a, which is preferably, as shown, straight or unbent throughout its length, is interposed between the two compression members, and is connected thereto, adjoining their ends, by horizontal rivets or bolts, 6. As shown in Figs. 1, 3, 5, 60 and 6, the tension member is a flat bar, set vertically or on edge, but it may, if preferred, be made of different section, as for example, a T bar, as shown in Fig. 7, or a plate of greater depth at its middle portion than at its ends, as shown in Fig. 8.

65

The compression members 1, are secured to the side plate, 2, by vertical bolts, 3, and the tension member, 1^a, is preferably turned laterally into end flanges, 1^a, which abut against the outer sides of the side plates and are secured thereto by horizontal bolts, 7, thus providing a substantial brace or tie from one side plate to the other. In cases where a T bar is used as the tension member, the end flanges, 1^a, may be formed upon the web, and the flanges of the bar may be turned downwardly to form flanges, 1^a, adapted to abut against the inner sides of the side plates.

70

The ridge pole, 4, and purlins, 5, are secured to the compression members by bolts, 4^a, and 5^a, respectively, and they may also be additionally secured in position by interposed distance blocks or abutments 80 of wood, bolted or otherwise secured to the tops of the compression members. As shown in Figs. 3, 4, and 6, the ridge pole and purlins are set between pairs of angles, 8, which are suitably secured to the compression members, and form pockets for the ridge pole and 85 purlins. It will be obvious that when the angles are employed, they perform the same function as abutments as the wooden distance blocks, and therefore that the latter would not be used.

A roof carline constructed substantially as above 90 described may be readily and inexpensively manufactured, and is of substantial strength and stiffness while comparatively light. The facilities which it affords for the support of the superposed roof structure and for the transverse bracing of the side plates will be apparent to those familiar with car construction.

I claim as my invention and desire to secure by Letters Patent:

1. A metal roof carline comprising two compression members of angle section, bent downwardly from their middle portions toward their ends, and a tension member or tie, interposed between the compression members and

95

100

connected thereto adjacent to their ends, which are adapted to fit in recesses in the side plates of a car frame, the tension member having lateral flanges adapted to lie longitudinally of and abut against the outer sides of the 5 side plates.

2. A metal roof carline comprising two compression members of angle section, bent downwardly from their middle portions towards their ends, a tension member or tie interposed between the compression members and con-

nected thereto adjacent to their ends, in combination 10 with the side plates of a car frame having recesses to receive the carline ends, the tension member having lateral flanges adapted to lie longitudinally of and abut against the outer sides of the side plates.

GEORGE B. MALTBY.
